UNITED STATES PATENT OFFICE.

CARL F. W. FIEBKE, OF ATHENS, WISCONSIN, ASSIGNOR OF ONE-TENTH TO OSCAR RADEMACHER, OF WESTBORO, WISCONSIN.

WHEEL BRIDGING FOR BAD ROADS.

Application filed February 4, 1928. Serial No. 251,973.

This invention relates to devices for bridging over bad portions of roads or devices for providing an effective bridging over mud holes and stretches of deep sand or the like, and the general object of the invention is to provide a relatively light track constructed of sheet metal which may be placed over portions of a bad road or places where there is no road or other stretches of sand or mud and constitutes a surface over which vehicles may pass.

A further object is to construct the bridging in sections which may be joined onto one another so as to form a continuous, smooth and interlocked roadway.

A still further object is to so construct the bridging as to prevent it from turning over.

Another object is to provide means for interlocking the sections to each other so as to prevent any sagging or dislocation at the joints, and to provide a bridging which may be readily taken up and the bridging stored or transported.

Other objects will appear in the course of the following description.

My invention is illustrated in the accompanying drawing, wherein:

Figure 1 is a fragmentary top plan view showing two sections of my road bridge;

Figure 2 is a transverse sectional view through one of said sections;

Figure 3 is a longitudinal sectional view showing two sections joined;

Figure 4 is a view of the extremity of one of the bolts;

Figure 5 is a plan view of the lock nut used in connection therewith.

Referring to this drawing, it will be seen that my improved bridging is constructed of a plurality of sheets of material, two sheets being shown designated A and B. These are preferably made of sheet metal, the strength and thickness of the sheet metal depending upon the weight of the traffic likely to pass over this particular stretch of roadway. If for heavy trucks, the bridging must be wider and thicker than for light automobile traffic. Each section A and B has the same form in cross section, namely the sheet 10 has a depressed middle portion 11 which gradually rises upwardly and laterally, as at 12, then is rounded, as at 13, downward and outward and then extends steeply downward and outward, as at 14, so as to form a cutting edge at the lateral ends of the sections

adapted to bite into the ground or other surface upon which the bridging is placed. Preferably each section will be approximately 18" in width and have any desired length, and preferably the lateral margins of the sections will extend about 1½" below the level of the middle portion 11. It will be understood, of course, that there is a track for each wheel and that each wheel will travel in the depressed middle portion of the bridge or track.

Extending transversely across the bridging below the sections is a truss rod 15 in the form of a bolt having a bolt head at one end and a lock nut at the other, this truss rod extending through the portions 14 and preferably bearing against the depressed middle portion 11. The middle portion 11 will be depressed approximately 3½", though obviously I do not wish to be limited to the particular dimensions.

Preferably, and in order to prevent the sections from tilting up, the sections A and B, and this applies to other sections as well, are formed to interlock. To this end, one 80 of the sections as, for instance, the section B is formed with a depressed portion 16 and the margin of the next adjacent section fits upon this depressed portion so that the surfaces of the two sections are flush with each 85 other. The flanges 14 of one section overlap the flanges of the adjacent section at this point and the truss rod 15 may pass through all four of these flanges, thus locking the sections at the joint.

In order to further prevent any tendency of one section to rise with relation to the other section and to interlock the sections with each other, one of the sections as, for instance, the section B is formed with a slit 95 17 which extends parallel to the end of the section and is located in the depressed portion 16. The material in front of this slit is slightly raised, as at 18. The section A is formed with a tongue 19 defined by the two 100 longitudinally extending slits 20. This tongue is depressed and when the end of the section A is placed over the adjacent end of the section B, the tongue 19 is inserted in the slit 17 and thus after the truss rod 15 is put in place the two sections are interlocked with each other so that they cannot have independent movement. The transverse rod 15 or bolt has a head at one end and the other end of the bolt has a flange 21 on each side 105 110

extending outward for approximately 2" to engage with a threadless lock washer 22 having a hole fitting the squared end 23 of the bolt. This lock washer is shoved past the flanges up to the side of the bridging and given a quarter turn which will lock the bolt in place until this action is reversed. The joint is now completed. At intervals of ten feet or so like bolts are inserted in the bridging for reinforcing purposes as at the joints.

The sections of the bridging may be of any desired length, and it is to be understood that the bridging might be curved so as to follow bends and curves in the road. When the bolts are withdrawn, the bridging may be taken up and the units placed one on top of another, making the bridging convenient for transportation and storage. The bridging may be used over any bad road or in any situation where it is necessary to bridge over a bad spot or a bad piece of land. Thus it may be used in deep mud, deep sand, over holes, over "washboard," effects in roads, over new construction, or where it is necessary to quickly improvise a road. Horse-drawn vehicles may also travel over this bridging without the bridging being displaced. Any number of units can be coupled together to make any length of track without sagging or dislocation at the joints because of the means whereby the sections are interlocked with each other. The wings formed by the downwardly and outwardly turned lateral margins of the bridging prevent the bridging from turning over for three reasons, first because of the width and low construction of the bridging, second because the extremity of each downwardly turned wing or flange will be forced into the ground while the middle portion rests upon the ground, and third because the soft ground, mud, muck or the like will pack or ridge up under each wing and this will have a tendency to suck downward upon the wing or upon the bridging as a whole, thus holding it in place. A vehicle can leave or enter the track over the wings or sides without tipping the bridging.

While I have illustrated an embodiment of my invention, I wish it understood that it might be varied in detail without departing from the spirit thereof. Thus, for instance, it is possible to fold the metal of the bridge upward over or beneath the wings so as to provide a double thickness at those portions of the bridge which support the

weight. This is illustrated in the drawing, but obviously where a lighter bridge is needed this double thickness may be left off.

I claim:

1. A wheel track consisting of a sheet of metal adapted to be laid down temporarily over a bad place in the road, the sheet having a depressed middle portion, upwardly and laterally inclined side portions, and downwardly extending lateral flanges, and bolts passing through said lateral flanges and beneath the middle portion and contacting with the middle portion.

2. A wheel track for roads consisting of a plurality of sheet metal sections adapted to be laid down temporarily over a bad place in the road, the sheet metal sections having one a longitudinally projecting tongue and the other a slit within which the tongue is engaged, and transversely extending bolts passing beneath the overlapped ends of the sections and engaging the sections with each other.

3. A track for roads consisting of a plurality of sheet metal sections adapted to be laid down temporarily over a bad place in the road and having a depressed middle portion and downwardly extending side flanges, one end of each section being depressed to receive the overlapped end of an adjacent section, the depressed portion being formed at its middle with a slit and the overlapping section being formed at its middle with a tongue adapted to be turned down and engage in said slot, and a transversely extending bolt passing through the overlapped flanges of the two sections and beneath the middle portions of the sections.

4. A wheel track for roads consisting of a plurality of sheet metal sections adapted to be laid down temporarily over a bad place in the road, the sheet metal sections having overlapping, interlocked, separable engagement with each other at the ends of the sections, the middle portion of each section being depressed and the lateral portions having downwardly extending flanges extending below the middle section and adapted to be forced into the road, and bolts extending through the overlapping lateral flanges of the sections and extending beneath and supporting the middle portion of the overlapping sections.

In testimony whereof I hereunto affix my signature:

CARL F. W. FIEBKE.
